FIG. 1.

FIG. 2.

Inventor:

Roscoe S. Heise
By D. Grunforth, L. C. Crittenden & Hiles,
Atty.

UNITED STATES PATENT OFFICE.

ROSCOE S. HEISE, OF MIDDLETOWN, OHIO, ASSIGNOR TO THE MIAMI CYCLE AND MANUFACTURING COMPANY, OF MIDDLETOWN, OHIO, A CORPORATION OF OHIO.

DESIGN FOR A BICYCLE-PEDAL.

57,901.

Specification for Design.

Patented May 17, 1921.

Application filed March 31, 1920. Serial No. 370,348. Term of patent 14 years.

To all whom it may concern:

Be it known that I, Roscoe S. Heise, a citizen of the United States, residing at Middletown, in the county of Butler, State of Ohio, have invented a new, original, and ornamental Design for a Bicycle-Pedal, of which the following is a specification, reference being had to the accompanying drawing, forming a part hereof.

In the drawing Figure 1 is a front plan view and Fig. 2 a longitudinal sectional view showing my new design.

I claim:

The ornamental design for a bicycle pedal, as shown.

ROSCOE S. HEISE.
